ENGINE CONTROL

Harry L. Johnson and Louis J. Johnson,
Waukegan, Ill.

Application January 16, 1933, Serial No. 651,978

1 Claim. (Cl. 123—98)

This invention relates in general to the speed control of an internal combustion engine and has more particular reference to the combining of the ignition and fuel feeding means for simultaneous 5 and separate operation.

An important object of the invention is to simplify and improve the control of a motor by combining the operation of a spark timing device and a carburetor having a throttle valve.

10 A further object of the invention is in the provision of a clutch connection for the throttle valve operated by the spark timing device.

A still further object of the invention is in the provision of means for manually operating a 15 throttle valve of a carburetor and for automatically operating the throttle valve when the spark timing device is operated.

A still further object of the invention is in the provision of an improved stop motion clutch in 20 connection with a carburetor throttle valve to provide for releasing and re-engaging the throttle valve at predetermined times during the movement of other engine controlling means.

Other objects of the invention will appear hereinafter, the preferred embodiment of the invention being illustrated in the accompanying drawings.

In the drawings, Fig. 1 is an elevation of an internal combustion engine embodying the invention;

30 Fig. 2 is a plan view with the magneto fly wheel in section;

Fig. 3 is a side elevation;

Fig. 4 is a sectional view of the carburetor; and

35 Fig. 5 is a detail view of the carburetor construction.

This invention is applicable to any internal combustion engine and is more particularly described in connection with the power plant of an 40 outboard engine in which there is a spark timing device and a carburetor. In starting such an engine a fixed position is given to the ignition device and to the control lever of the fuel feeding device or carburetor; the engine crank shaft is 45 then rotated by means of a rope starter or other means and the engine is supposed to continue operation in a normal manner and to be controlled by advancing or retarding the spark and by manipulating the throttle of the carburetor.

50 It is particularly difficult to properly actuate both of these speed controlling devices accurately and promptly in an outboard engine, particularly when the boat to which it is applied is in rough water. The present invention is therefore designed and intended to provide a simple co-ordi-

nated control for both the ignition device and the carburetor throttle valve which is easily actuated by moving a convenient and accessible lever.

Referring now more particularly to the drawings, a conventional outboard motor power plant is shown comprising an engine 10, crank case 11 to which a carburetor 12 is connected, a fuel tank 13 connected with the carburetor by a supply pipe 14 having a control valve 15 therein. Partially extending into a recess 16 of the fuel tank is a fly wheel magneto having an outer casing 17 rotatable with the engine shaft 18 which shaft carries a notched starter plate 19 at its upper end above the magneto.

To advance and retard the ignition spark for the engine, there is a plate 20 movable freely about the shaft 18 and located within the casing 17. This plate carries an ignition timing device comprising a relatively fixed contact 21 and a pivoted breaker arm 22, one end of which has a projection 23 adapted to engage a cam 24 on the engine shaft 18 for interrupting the ignition circuit for the engine. To vary the point of operation of the ignition breaker, the plate 20 is set in different positions by means of a lever or handle 25, thus causing the spark to be advanced or retarded and producing a corresponding well known variation in operation of the engine.

The carburetor 12 has a float chamber 26, to 30 which the fuel is admitted from the fuel tank 13, through the pipe 14, and adjacent the fuel chamber is a casing 27 within which is a throttle valve 28 for varying the supply of fuel which is drawn from the carburetor. This valve 28 is rotatable 35 upon opposite shaft extensions 29 and 30 which extend through the bottom and top 31 of the casing 27.

Connected to one of the shaft extensions 30 is 40 a throttle arm 32 adjustably secured thereto by a set screw 33 and having a projection 34 adapted to engage either one of the adjustable set screws 35 or 36 positioned in outward projections 37 of the cover 31. Thus the movement of the arm 32 will move the throttle valve 28 in any position 45 between the limits of the set screws 35 and 36.

The above described structures are the conventional forms now employed in outboard motors and to co-ordinate their movement and operation the plate 20 of the ignition device is provided with 50 a projection 41 and an operating arm 42 is mounted upon the shaft extension 29 of the carburetor which are connected by a link 43. As their movements are not exactly in line a ball projection 44 is mounted at the end of arm 42, 55

the projection 41 being similar thereto and the connectors 45 are adjustable at the ends of the link 43 for producing universal joints.

The arm 42 is rotatable upon the shaft extension 29 of the curvature, but is not rigidly attached thereto, a flexible connection being provided therewith by means of a collar 46 secured to the extension by a pin 47 extending therethrough and located at a distance from the bottom of the casing 27 so that the arm 42 and its bearing extension 48 may slide along the shaft extension 29 but is normally pressed in the direction of the collar 46 by a spring 49 partially surrounding the extension 48. In the collar 46 there is a recess 50 for receiving a clutch ball 51 and in the arm 42 is a seating recess 52 for receiving the ball 51 in a predetermined position.

This structure provides for a lost motion connection between the arm 42 and the throttle valve 28 and the arm is so positioned that when the throttle arm 32 engages one of its limiting set screws 35, or 36, the continued movement of the spark timing device by the handle 25 will cause a further movement of the arm 42 without any movement of the valve 28. This is effected by means of the clutch ball 51 which holds the arm 42 and the collar 46, which is attached to the throttle valve yieldingly together during the full range of movement of the throttle valve but permits the arm 42 to swing away from the collar 46 against the pressure of spring 49 thereby unseating the clutch ball 51 from the recess 50 of the

collar 46 when the arm 42 is moved beyond the path of movement of the throttle valve. The ignition control device, may therefore be moved to retard the spark even after the throttle is in its minimum opening or limiting stop position. In the other direction of movement of the ignition control lever from its spark retarding position, the arm 42 is moved a predetermined distance before the clutch ball 51 is again engaged with the recess 50 thereby connecting the arm 42 to the throttle valve extension 29 for correspondingly operating the throttle.

We claim:

In an outboard motor, in combination, an internal combustion engine, an ignition timing device having a movable plate with an extending handle, a fuel feeding device having a control valve rotatable therein, a shaft projecting from the fuel feeding device upon which the valve is mounted, means at one end of the shaft for limiting the rotative movement of the valve, a spring pressed arm rotatable on the shaft, a resilient clutch connection between the shaft and the arm, and a link connecting the outer end of the arm and the movable timing part so that the movement of the handle of the timing part will cause a corresponding movement of the valve throughout a part of the movement of the arm, the arm and the timing plate being released from connection with the valve when the arm is moved beyond the limit of movement of the valve.
